FRAME FOR WOMEN'S STRAPLESS GARMENTS

Helen Taubkins Snider, Baltimore, Md.

Application February 23, 1940, Serial No. 320,470

5 Claims.

(Cl. 2-42)

This invention relates to women's garments of the so-called "strapless" type designed to cover the breasts and which dispenses with the use of straps encircling the neck, shoulders or back, above the waist, for holding the garment in place. Among such garments may be mentioned bathing suits, sport clothes, evening gowns and brassières, although the invention is not to be regarded as restricted to use with such garments.

An important object of my invention is to provide a frame serving as a foundation for garments of the above character, the frame being of light, strong and simple construction and adapted to be comfortably worn in a concealed position, the parts being so flexibly connected as to be readily yieldable in various directions in order not to interfere with the free and natural movement of the body.

Other objects and advantages will be apparent from the following detailed description of a preferred embodiment of the invention, reference being had to the annexed drawing in which the figure is a view of one form of my garment frame showing the manner in which it is adapted to be supported upon the body.

In the drawing illustrating a strapless brassière incorporating my invention, I designate an abdominal piece composed of some light material such as aluminum alloy. This abdominal piece is curved so as to snugly fit the body of the wearer (indicated in phantom outline) and extends, increasing in width, from the crotch upwardly along the abdomen. While the size and shape of this abdominal piece will lend themselves to variations, I prefer to extend this piece upwardly to approximately one inch above the navel and to make it approximately seven inches in width adjacent its upper end so as to afford an extensive and stable area of contact with the body. The abdominal piece may be secured to the body by means of a belt 2 secured at one end within slots 3 and passing over the hips and between the legs to connect with the lower end of the piece, as indicated in the drawing. Breather holes 4 extend through the abdominal piece to afford ventilation for the underlying skin.

Pivoted to the upper end of the abdominal piece by means of a pin 5 so that its lower end overlies the abdominal piece is a vertically disposed stay 6. This stay is composed of light spring steel, preferably stainless, so as to be readily flexible outwardly of the body but is slightly bowed in a manner such as to exert a resilient pressure inwardly against the body so that the stay lies close to the body.

The stay 6 extends upwardly medially of the front position of the body and at its upper end terminates between the two breasts, as shown in the drawing. Forming part of the stay is a cross-piece 7 which overlies the stay adjacent its upper end and is pivotally connected thereto by means of a pin 8. This pin extends through registering openings in the stay and crosspiece and may be releasably held by a nut threaded upon the projecting end of the pin. For permitting the vertical adjustment of the crosspiece upon the stay, the openings upon the stay for passing the pin 8 may be duplicated at short intervals along the stay as indicated at 9.

15 At each end of the crosspiece 7 is carried a pin 10 pivotally supporting a stainless steel wire loop 11 adapted to encircle a breast. This loop may be either round or oval in shape and may be curved out of a plane so as to conform to the contour 20 of the chest wall. The steel wire composing the breast loops is sufficiently deformable to allow molding the loops to individual tastes but yet is rigid enough to retain its shape under ordinary conditions of use. The loops 11 are adapted to 25 be covered by fabric 12 to conceal the wire frame and to complete the brassière.

It will be apparent from the foregoing description that freedom of movement of the body is afforded by my garment frame. When the body 30 is bent either to the right or left at the waist the frame will pivot about the pin 5; when bent at the shoulders the loops 11 will pivot about their pins 10 and the crosspiece will swing about the pin 8; and when moved either forwardly or 35 backwardly the stay will flex so as to partake of this bodily movement. During normal activity, the action of the body will usually involve a combination of such movements but under any conditions my garment frame, by virtue of its 40 flexible construction, is enabled to yield without interfering with such motion. Also because of its light and simplified construction the frame is adapted to be comfortably and inconspicuously 45 worn with sheer evening gowns. Adjustment for differences in the height of women is conveniently afforded by the releasable pin 8.

While I described my invention in connection 50 with a strapless brassière, it will be apparent that it may be employed as the foundation of other types of garments that include a breast-covering portion so as to avoid the use of visible straps or bands extending over the shoulders, about the neck or across the back above the 55 waist. The abdominal piece 1 may, if desired, be

incorporated in and form a part of a belt or girdle of conventional type.

Obviously various other changes in detail and design may be made in the frame described above without departing from the spirit of my invention.

I claim:

1. A frame for women's strapless garments comprising a stiffly flexible stay adapted to extend medially of the front part of the body from adjacent the abdomen to a position intermediate the breasts, an abdominal piece arranged to be worn upon the body, means for attaching said abdominal piece to the body, means pivotally connecting the lower end of the stay to said abdominal piece, a member engaging and supporting each breast, and means pivotally connecting said member to the upper end of the stay, whereby said members and stay are movable about separate pivots so as not to interfere with the free movement of the body.

2. A frame for women's strapless garments comprising a stiffly flexible stay adapted to extend medially of the front part of the body from adjacent the abdomen to a position intermediate the breasts, an abdominal piece arranged to be worn upon the body, means for attaching said abdominal piece to the body, means pivotally connecting the lower end of the stay to said abdominal piece, a loop member for encircling each breast, said stay adjacent its upper end having a crosspiece pivotally secured thereto, and means pivotally connecting each of said loop members to said crosspiece, whereby the loop members, crosspiece and stay are movable about separate pivots so as not to interfere with the free movement of the body.

3. A frame for women's strapless garments comprising a stiffly flexible stay adapted to extend medially of the front part of the body from adjacent the abdomen to a position intermediate the breasts, an abdominal piece arranged to be worn upon the body, means for attaching said abdominal piece to the body, means pivotally connecting the lower end of the stay to said abdominal piece, a loop member for encircling each breast, and means pivotally connecting said loop

member to the upper end of the stay, said abdominal piece being curved to fit the contour of the body and extending from the crotch upwardly along the abdomen, whereby the loop members and stays are movable about separate pivots so as not to interfere with the free movement of the body.

4. A frame for women's strapless garments comprising a stiffly flexible stay adapted to extend medially of the front part of the body from adjacent the abdomen to a position intermediate the breasts, an abdominal piece arranged to be worn upon the body, means for attaching said abdominal piece to the body, means pivotally connecting the lower end of the stay to said abdominal piece, a loop member for encircling each breast, and means pivotally connecting said loop member to the upper end of the stay, said abdominal piece being curved to fit the contour of the body and extending from the crotch upwardly along the abdomen, said abdominal piece expanding upwardly and outwardly to provide a substantial area of contact with the body and having breather holes therein for ventilating the underlying skin, whereby the loop members and stay are movable about separate pivots so as not to interfere with the free movement of the body.

5. A frame for women's strapless garments comprising a stay composed of spring metal adapted to extend medially of the front part of the body from adjacent the abdomen to a position intermediate the breasts, an abdominal piece composed of light rigid material arranged to be worn upon the body, said abdominal piece being adapted to extend upwardly from the crotch to the vicinity of the navel, means for attaching said abdominal piece to the body, means pivotally connecting the lower end of the stay to the upper end of said abdominal piece, a wire loop member encircling each breast, a fabric covering supported upon said loop member and means pivotally connecting said loop member to the upper end of the stay, whereby the loop members and stay are movable about separate pivots so as not to interfere with the free movement of the body.
